(57) **CLAIM**

The ornamental design for a food product container with closure, as shown and described.

DESCRIPTION

FIG. 1 is a perspective view of a food product container with closure showing our new design, the broken lines of the container are for illustrative purposes only and form no part of the claimed design;

FIG. 2 is a top plan view of the embodiment illustrated in FIG. 1;

FIG. 3 is a bottom plan view of the embodiment illustrated in FIG. 1;

FIG. 4 is a front elevational view of the embodiment illustrated in FIG. 1;

FIG. 5 is a rear elevational view of the embodiment illustrated in FIG. 1;

FIG. 6 is a side elevational view of the right side of the embodiment illustrated in FIG. 1; and,

FIG. 7 is a side elevational view of the left side of the embodiment illustrated in FIG. 1.
